(57) **CLAIM**

The ornamental design for a display screen or portion thereof with an animated graphical user interface, as shown and described.

DESCRIPTION

The file of this patent contains at least one drawing/photographs executed in color. Copies of this patent with color drawings(s)/photographs(s) will be provided by the office upon request and payment of the necessary fee.

FIG. 1 is a front view of a display screen or portion thereof with an animated graphical user interface showing a first image in a first sequence showing my new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof;

FIG. 9 is a ninth image thereof;

FIG. 10 is a tenth image thereof;

FIG. 11 is an eleventh image thereof;

FIG. 12 is a twelfth image thereof;

FIG. 13 is a thirteenth image thereof; and,

FIG. 14 is a fourteenth image thereof.

The broken line showing of the display screen, text, and graphic features forms no part of the claimed design. Some of the Figures include dash-dot-dash broken lines extending horizontally, and in those Figures, the portions of a display screen or portion thereof that lie below the dash-dot-dash broken line form no part of the claimed design. The appearance of the animated graphical user interface sequentially transitions between the images shown in FIGS. 1-14 according to an embodiment. The process or period in which one image transitions to another image forms no part of the claimed design.
